UNITED STATES PATENT OFFICE.

EMIL O. STARKE, OF OAK PARK, ILLINOIS, ASSIGNOR TO THE RUDOLPH WURLITZER COMPANY, OF CHICAGO, ILLINOIS, A CORPORATION OF ILLINOIS.

HARP DAMPER.

Application filed June 28, 1922. Serial No. 571,458.

The purpose of this invention is to provide an improvement in harps, consisting of a damper for the strings, and means for reliably operating the same, preferably by a pedal. It consists in the elements and features of construction shown and described, as indicated in the claims.

In the drawings:

Figure 1 is a side elevation of the upper part of a harp equipped with this invention.

Figure 2 is a detail section of the base of the harp showing the pedals and connections for operating the damper.

Figure 3 is a side elevation of one of the damper-supporting bars and the damper operating cams thereon, with the operating connections thereto.

Figure 4 is a section at the line, 4—4, on Figure 1, on an enlarged scale.

Figure 5 is a detail plan view of a portion of the damper carrying bars and portion of the damper adjacent thereto with one of the damper operating plungers and its cam.

Figure 6 is a section at the line, 6—6, on Figure 5.

Figure 7 is a section at the line, 7—7, on Figure 5, showing the cam rocked for advancing the plunger.

Figure 8 is a detail section at the line, 8—8, on Figure 7.

In the structure shown in the drawings, A is the pillar of the harp, B is the body, C is the neck and D, D, are the action plates for supporting the ordinary harp action, a certain element of which is shown at E (though not concerned in this invention). F, F are damper-carrying plates which are mounted on the lower end of the action plate and constitute in effect the extension of said plate, but which are themselves braced together by cross posts, F¹, F¹, so that the construction embodying this invention may be applied to and removed bodily from the harp. In the frame structure comprising the damper-carrying plates, F, F, there are mounted a plurality of plungers, G, their mounting being effected by means of pivot studs, H, secured by screws, J, to the inner side of the one of the bars, F, which is more remote from the strings, and the plungers, G, are reduced in diameter at one end portion for being mounted co-axially bored to fit slidably upon said studs, H. Each of these

plungers is provided with a spring, K, interposed between the bar, F, and the shoulder, h, adjacent the reduced part of the plunger, as seen clearly in Figures 4, 5 and 6. On the ends of the plungers toward the strings, 60 there is secured a damper-carrying bar, L, on which there is mounted the damper, M, of felt or like suitable material. Mounted for rocking upon the studs, H, are cams, N. These cams and the plungers, G, are externally cylindrical and of the same diameter and their proximate faces are oblique to the cylinder axis so that as they stand in normal position, with the damper retracted from the strings by the reaction of the springs, K, 70 they constitute substantially a right cylinder diagonally slit. From this construction it will be understood that upon the rocking of the cams, N, about the studs, H, the plungers, G, will be forced against the reaction of 75 the springs, K, in direction for carrying the damper against the strings; and that by simultaneously rocking all the cams the damper will be carried simultaneously 80 throughout its entire length so as to damp the strings simultaneously. For so rocking the cams they are each provided with a short lever arm, N¹, and these lever arms are connected successively along the entire length of the bars, F, corresponding to the contour 85 of the action plate, D, by a continuous slightly flexible link, or, if preferred, by individual links, O, running from each lever arm, N¹, to the next so as to operate substantially as a continuous connecting linkage, 90 the upper end of which or the last of said links, O, being connected to the arm, P¹, of the bell crank lever, P, which is mounted at the head of the pillar, A, overhanging the axial cavity of said pillar if it is hollow as 95 shown. From said bell crank lever arm an operating rod, Q, extends down along the pillar and is connected at its lower end to a pedal, R, fulcrumed at r on the harp base, 100 with its pedal, R¹, in a position for operation by the player who will depress the pedal when he desires to advance the damper against the strings.

Upon considering the cam relation of the two parts, N and G, having their oblique faces abutting, it will be seen that as the cam, N, is rocked about the axis upon the first slight movement from position of complete abutment of the two faces upon each other, as seen in Figure 6, they would re- 110

main in contact only at a single point upon the elliptical periphery of the cam; from which it would result that this periphery of the cam would rapidly wear or wear the opposing cam face of the plunger. To avoid this result and to provide a more satisfactory wearing surface for the two members upon each other, the elliptical cam edge of the plunger, G, may be rounded, as seen at *g*, in Figure 8, so as to be curvilinear in radial section at all parts of the edge which will constitute the wearing surface of the cam upon the plunger in the rocking action described.

15 I claim:

1. In combination with a harp having a curved neck of conventional outline, a damper bar of similar outline disposed below said neck adjacent the strings of the harp, a pair of plates similar in outline to said bar and mounted in spaced relation to register horizontally therewith, a series of plungers attached to the damper bar at intervals in its length and slidably mounted in one of said plates, each of said plungers having an axial bore and a guide stud rigidly carried by the other plate extending into said bore of the plunger, said plunger being formed with a cam follower at its inner end disposed between said plates, and a cam rotatably mounted on the stud between the follower and the plate from which said stud projects, together with means for rocking all of said cams simultaneously to force the damper bar against the strings.
2. In combination with a harp having a curved neck which includes a pair of curved action plates embracing a downwardly open space back of the strings, a damper bar of curved outline similar to that of the neck mounted adjacent the strings below said ac-

tion plates and a pair of carrying plates for said bar extending respectively from the lower edges of the action plates and spaced apart to accommodate actuating mechanism for the bar, said mechanism comprising plungers attached to the damper bar at intervals in its length, extending perpendicularly from the plane of said bar and slidably mounted in one of said carrying plates, a cam associated with each plunger and rockable about the axis thereof for moving the bar toward the harp strings, together with links connecting said cams for simultaneous operation and disposed between the two carrying plates, said plates being of such width as to fully mask said links throughout the length of the damper bar.

3. In combination with a harp having a curved neck, a damper bar of curved outline similar to that of the neck mounted adjacent the strings below the neck and a pair of carrying plates for said bar of like outline with the bar spaced apart and mounted behind it extending throughout the length of the bar; plungers attached to the damper bar at intervals in its length extending perpendicularly from the plane of said bar and slidably through one of the carrying plates; cam means associated with each plunger and rockable about the axis thereof for moving the damper bar toward the harp strings, together with links disposed between said carrying plates and curved to lie within the outlines thereof so as to be fully masked by said plates, said links connecting the cams for simultaneous operation.

In testimony whereof, I have hereunto set my hand at Chicago, Illinois, this 17th day of June, 1922.

EMIL O. STARKE.
